NUMBER-DISPLAYING DEVICE

Joseph Lesniak, Dearborn, and John A. Donnelly,
Detroit, Mich.

Application June 30, 1952, Serial No. 296,358

1. Claim. (Cl. 40—10)

1 Our invention pertains to a device adapted for use on patterns employed in industrial shops and is particularly desirable where numerals identifying a specific pattern or other tool have to be changed quickly. To make this aspect of our invention more understandable, it will be mentioned here that according to the general practice patterns are provided with a recess wherein numerals such as set forth the date and a reference to the day or night shift are soldered in place and have to be removed when a new set of numerals are to be inserted in their place. In some industrial establishments this is done daily and sometimes twice a day.

Obviously, soldering numerals in place is a wasteful and time-consuming operation. It is in order to make the change of numerals an easy procedure capable of being accomplished easily and quickly, without the use of any tools except a screwdriver, that we have made our improvement.

Our invention calls for a special holder and a plurality of movable blocks fitting into said holder. The latter is of a specific design making the insertion of numerals or their removal for the purpose of substitution of others an easy matter requiring but little time.

We shall now describe our invention with reference to the accompanying drawing in which:

Fig. 1 is a top elevational view of our device as set within a recess of a pattern; 30

Fig. 2 is a sectional view on line 2—2 of Fig. 1;

Fig. 3 is a sectional view on line 3—3 of Fig. 2;

Fig. 4 is a sectional view on line 4—4 of Fig. 2;

Fig. 5 is a perspective view of a holder for numerals and a member to be used in combination therewith.

Similar numerals refer to similar parts throughout the several views.

The principal element of our number-displaying device is an oblong holder best shown in Fig. 5 and generally identified by numeral 10. It includes a flat bottom 11 and two side rails or flanges 12 which extend from one end 13 of said holder to a line spaced from the opposite end 14 thereof. As a result the portion of the holder from said line to said last-named end has the shape of a flat plate 15 devoid of any side flanges.

At the first-named end 13 the holder includes a shallow plug 16 disposed between the two flanges, while access to the space between the flanges endwise may be had from the direction of said plate 15. The opposed faces of the sides of said flanges are undercut so that at the 50

top the distance between them is smaller than at the level of the bottom 11 of said holder.

As the holder is to be affixed to a pattern, it is provided with holes for application of screws by means of which it is to be kept in place. For that purpose the pattern is usually provided with a recess or a shallow slot. Such a recess is marked by numeral 17. At one end adjoining plug 16 the holder is provided with a hole 18. A screw 19 passing through said hole is threaded into the body of the pattern 20. At the opposite end the holder contains another hole 21 to which we shall refer presently.

Slidably fitting into the holder from the opposite end thereof, that is, from the direction of said end plate 15, are a plurality of blocks 22, each of them carrying a numeral, a letter, or any other indicia. Each block as seen endwise has the form of an isosceles trapezoid in which the top is narrower than the base. The sides of each block will be in abutment with the undercut faces of the flanges of the holder, this arrangement preventing the blocks from falling out from their respective places. In addition to the blocks carrying numerals or other signs, we are employing at least one block 23 to fit over the top of screw 19 so as to conceal it. This, however, is simply a matter of choice.

Upon insertion of this blank block, blocks 22 carrying numerals or other indicia are slid into the holder one by one as desired, whereupon in order that they may not be displaced endwise we are using a locking member 24. The member is of the same width as said plate 15 and has a square, cut-off end 25 for abutment with the free ends of flanges 12. It is also provided with a hole 26 which, when the locking member is positioned upon plate 15, will be in alignment with hole 21, permitting application of a screw 26a. The latter is to be threaded into the body of pattern 20.

Once the holder has been secured to a pattern within a recess made for this purpose, the blocks carrying numerals may be changed without the need of removing the holder from said recess. Blank block 23 which covers the top of screw 19 retains its position permanently. However, in order to remove from the holder said numeral-carrying blocks 22 it is necessary to remove screw 26a and to lift the locking member 24. The locking member being off, all of the blocks or any of them may be slid out and new blocks may be substituted in their place, whereupon the locking member 24 is again employed and secured in its

position by means of screw 26a to prevent the blocks from sliding out of the holder.

It will be understood that some changes may be made in the structure of our device without departing from the inventive principle disclosed herein.

What we, therefore, wish to claim is as follows:

A number-displaying device for patterns, the device including an oblong holder having a flat bottom and being closed at one end, a flange along bottom and being closed at one end, a flange along each side, the spacing between the flanges at the top being smaller than at the level of said bottom, said flanges extending from one end of the holder to a line spaced from the opposite end thereof, the portion free of flanges forming a flat end 15 plate, the holder being provided at one end remote from said plate with a hole for insertion of a screw to be threaded into the pattern, while the end plate is provided with a similar hole, a plurality of blocks adapted to fit end- 20 wise into the holder from the direction of said end plate and to be retained within the holder

by said flanges, individual blocks carrying numerals or other indicia for display between said flanges, and a locking member adapted to be positioned over the end plate for abutment with the free ends of the flanges, the locking member being provided with a hole in alignment with the hole in the plate, and a screw adapted to pass through both holes to keep the locking member in place upon said holder and to secure the holder to the pattern.
